(57) **CLAIM**

We claim the ornamental design for a telephone handset, as shown and described.

DESCRIPTION

FIG. 1 is a front perspective view of the telephone handset;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines that show the outermost periphery of non-claimed features represent the boundaries of the claimed design. All other broken lines are directed to environment and are for illustrative purposes only. The broken lines and the unshaded regions defined by broken lines form no part of the claimed design.

The shading illustrated in the figures (except the diagonal shading on the display screen) is provided merely to represent the contour of the design and is not intended to be illustrative of texture, gloss, or surface decoration.
